B.F. Adams,

Cheese-Cutter,

No 8,501,

Patented Nov. 11, 1851.

UNITED STATES PATENT OFFICE.

BENJ. F. ADAMS, OF BANGOR, MAINE.

CHEESE, BUTTER, AND BREAD CUTTER.

Specification of Letters Patent No. 8,501, dated November 11, 1851.

To all whom it may concern:

Be it known that I, BENJAMIN F. ADAMS, of Bangor, in the county of Penobscot and State of Maine, have invented a new and 5 useful Machine called the "Cheese, Butter, and Bread Cutter," of which the following is a full and exact description.

An oblong triangular frame (A A A A) about two feet and six inches long on two 10 sides, one foot eight inches on the third side; three legs (b b b) three inches long; from the base of the frame rise three posts (c c c) one from each corner, two feet in height; upon the top of the posts is a part of the 15 frame corresponding with the base of the frame; a screw on each end of the posts passes through the base and top parts of the frame and is fastened with nuts (d d d), thus completing the frame.

20 A circular revolving table (e) is set over the top of the frame upon a shaft (f) which passes through the top of the frame and extends through a cross-beam in the top of the frame to a corresponding beam (g) 25 in the base of the frame, and rests in a socket (h) in said lower beam. Upon the top of the shaft are several horizontal arms upon which the table is supported; another vertical shaft (i i) near the right hand corner of the short side of the frame, passes down through the top of the frame and a spur (j) or arm below in the post at the right of the short side of the frame, and is attached to the treadle (k); at the top of 30 this shaft is attached a knife (l) three or four inches wide at the shoulder, and about eleven inches long, and one eighth of an inch thick in the center, and ground concave from

the center to the top and bottom on both sides of the knife. The knife is so connected with the shaft as to turn upon it until it points to the center of the table when it stops to be drawn down by the treadle. Near the lower end of this shaft, and half the length of the knife from the shaft is a 40 hook (m) connecting with the treadle; the treadle is attached to the post at the small corner of the frame by a spur (q) six inches from the bottom, and extends six inches outside of the long end of the frame turns 45 downward and ends with a step (n) for the foot. The treadle and knife shaft are raised by a pulley (o o) and weight (p).

What I claim as my invention and desire to secure by Letters Patent is,

55 The arrangement of the circular revolving table (e) and knife (l), the said knife being attached to the sliding shaft (i) and operated by means of a treadle (k) and weighted cord and pulley or their equivalent, so that 60 the cheese or other article to be cut may be placed upon the table and not removed until by a single revolution of the wheel, and a few slight pressures of the foot upon the treadle, it is cut into as many parts as may 65 be desired without crumbling or waste.

In witness whereof I the said BENJAMIN F. ADAMS have hereunto subscribed my name in the presence of the witnesses, whose names are hereto subscribed, at Bangor, on the 70 eighteenth day of March in the year 1851.

B. F. ADAMS.

Signed, sealed and delivered in presence of—

JOHN E. GODFREY,
BENJN. E. GALLUP.
